LADY'S SLIP

Ethel B. Elliott, Los Angeles, Calif.

Application August 15, 1952, Serial No. 304,583

3 Claims. (Cl. 2—73)

1

The present invention relates generally to the field of clothing, and more particularly to a novel and improved lady's slip.

There exists today two general types of ladies' slips, namely, the conventional full slip comprising a skirt portion and upper body covering or bodice portion attached thereto, and a half slip, which latter slip consists of solely a skirt portion. The full slip affords two major advantages over the half slip. Firstly, it offers the wearer more protection respecting the outer garments, and secondly, it may not readily be twisted about the body by virtue of its suspension from shoulder straps, or the like. The half slip, on the other hand, affords an advantage over the full slip in that the half slip does not in any way conceal or soften the more pleasing details of the natural or brassiére bust line of the wearer as does the full slip; the front of the bodice portion of a full slip extending over the breast area of a wearer so as to exert a "bridging" effect between the breasts. This is at present considered to be an important advantage in view of the recent improvements in brassières, both with regard to the breast-molding qualities, as well as their appearance; certain dress fashions calling for an exposure of the upper decorative part of the brassière.

It is a major object of the present invention to provide a novel lady's slip which combines the advantages of a full slip with those of a half slip. More particularly, a slip embodying the present invention will afford adequate protection to a wearer's outer garments, remain in its proper location without twisting, and yet will not conceal or soften the lines of the wearer's breasts.

It is a further object of the present invention to provide a lady's slip which will not sag when worn, but instead will remain substantially form fitting to a wearer's torso.

Another object of the present invention is to provide a lady's slip which is adapted for use by ladies of varying body heights and sizes.

A yet further object of the present invention is to provide a lady's slip which may be worn with various styles of dresses.

An additional object of the present invention is to provide a lady's slip which will not be difficult to manufacture nor require special materials in its construction.

Other objects and advantages of the present invention will become apparent from the following detailed description taken in conjunction with the appended drawings, wherein:

Fig. 1 is a general perspective three-quarter

2

front view of a lady's slip embodying the present invention as it appears when being worn;

Fig. 2 is a general perspective three-quarter rear view of said lady's slip;

Fig. 3 is a general perspective three-quarter front view of an alternate form of lady's slip embodying the present invention; and

Fig. 4 is a general perspective three-quarter front view of another alternate form of lady's slip embodying the present invention.

Referring to the drawings, and particularly to Figs. 1 and 2 thereof, a lady's slip embodying the present invention will broadly comprise a skirt portion 10 and an upper body-covering portion 12 secured at its lower edge to the upper edge of the skirt portion, which upper body portion will be supported from the shoulders 14 of a wearer 15 by means of suitable shoulder straps 16, or the like. The front of the upper body-covering portion 12 is seen to be formed with an opening 18 in the breast area of sufficient width and depth that the major portion of the breasts 19 of the wearer 15 will not be covered by the upper body-covering portion. With this arrangement, it will be apparent that a lady's slip embodying the present invention will not in any way conceal or soften the more pleasing details of the wearer's bust line.

More particularly, the skirt portion 10 and the upper body-covering portion 12 will preferably be interconnected by a waistband 20, which waistband will be formed of a material having sufficient circumferential resilience to cause it to snugly engage the waist of the wearer 15. To this end, the waistband may be formed of the same material from which the skirt and upper body-covering portions are made, but will comprise a double layer of such material cut on the bias in a conventional fashion. Alternatively, elastic material (not shown) may be disposed along the circumference of the waistband in place of such bias-cut material.

In the form of slip shown in Figs. 1 and 2, it will be noted that elastic material 22 is shown as forming the outline of the opening 18. The present invention contemplates that such elastic material 22 will cooperate with the waistband 20 when the slip is being worn to make the upper body-covering portion 12 of substantially form fitting with respect to the upper torso of the wearer 15. This arrangement is particularly to be desired where the slip is to be worn underneath a dress of the form fitting type. The shoulder straps 16 are seen to interconnect the upper ends of the opening 18 with the rear of the upper

body-covering portion 12. Preferably each shoulder strap will include a buckle 24 whereby the effective length of these straps may be adjusted. It has also been found desirable to provide the slip with short strap means 26 which connect the upper edge of the upper body-covering portion 12 outwardly of the opening 18 with each of the shoulder straps 16 at a point thereon below the buckle 24. With particular reference to Fig. 1, the slip may also be provided with a horizontal elastic cross-piece 28 interconnecting the sides of the opening 18 above the lower extremity thereof but below the breast area of the slip. Where this cross-piece is utilized, the portion 29 of the waistband between the cross-piece and the lower extremity of the opening 18 may be eliminated. The provision of this cross-piece has been found to improve the form fitting qualities of the upper body-covering portion 12.

Referring now to Fig. 3, there is shown an alternate form of lady's slip embodying the present invention, which form has been found to be especially well adapted for use with women having somewhat larger than normal figures. This alternate form of lady's slip is in general similar to that shown in Figs. 1 and 2; the exception being the termination of the lower extremity of the opening 18' at a point higher than was the case in the aforescribed slip. Additionally, the elastic cross-piece 28 shown in Fig. 1 is not utilized. The remaining elements of this alternate form of slip are seen to be similar to the parts of the aforescribed slip, with the further exception that the waistband 20' is not cut away in the front.

Referring now to Fig. 4, there is shown another alternate form of lady's slip embodying the present invention. This form of slip is especially suited for use with evening wear and with summer dresses. With this form of slip, the opening 18'' is shown as being outlined by a resilient material other than elastic, which material 30 may conveniently consist of the same material from which the skirt and upper body-covering portions are formed but utilized in a double layer cut on the bias.

The supporting means for the upper body-covering portion 12'' of this form of slip may be a shoulder strap 32 of the halter type, which shoulder strap will preferably be formed of an elastic material. This shoulder strap 32 is seen to interconnect the upper edges of the opening 18'' and is adapted at its intermediate portion to encircle a wearer's neck. The waistband 20'' will preferably be formed of the same material from which the skirt and upper body-covering portion is formed but will consist of a double layer of such material cut on the bias. There is also shown elastic strap means 34 connecting the upper edge of the upper body-covering portion 12'' outwardly of opening 18'' with the sides of the shoulder strap 32. With this arrangement, it is contemplated that the shoulder strap 32 and strap means 34 will cooperate with the waistband 20'' to make the upper body-covering portion substantially form fitting to the upper torso of a wearer.

It will be apparent from the foregoing description that a lady's slip constructed in accordance with the present invention will provide a wearer with the advantages of both a full and a half slip without the disadvantages normally attributed to such slip. It will also be apparent that various modifications and changes may be made with regard to the ladies' slips herein-

before set forth without departing from the spirit of the invention or the scope of the appended claims.

I claim:

5 1. A lady's slip, comprising: a skirt portion; a waistband at the upper edge of said skirt portion formed of a material having sufficient circumferential resilience to cause said band to snugly engage the waist of a wearer; an upper body-covering portion secured at its lower edge to said waistband, the front of said upper body-covering portion being formed with an opening in the breast area substantially across the width of said portion and from a point adjacent said waistband upwardly in order that the major portion of a wearer's breasts will not be covered by said upper body-covering portion; elastic material secured to the front of said upper body-covering portion so as to form the outline of said opening; a horizontal elastic crosspiece interconnecting the sides of said opening adjacent the upper edge of said waistband, said waistband being cut away therebelow to define a separate frontal opening, said elastic material and said

10 crosspiece cooperating with said waistband when said slip is being worn to make said upper body-covering portion substantially form fitting to the upper torso of a wearer; and, shoulder straps connecting the front and rear of said body-covering portion.

20 2. A lady's slip, comprising: a skirt portion; a waistband at the upper edge of said skirt portion formed of a material having sufficient circumferential resilience to cause said band to snugly engage the waist of a wearer; an upper body-covering portion secured at its lower edge to said waistband, the front of said upper body-covering portion being formed with an opening in the breast area substantially across the width of said portion and from a point adjacent said waistband upwardly in order that the major portion of a wearer's breasts will not be covered by said upper body-covering portion; elastic material secured to the front of said upper body-covering portion so as to form the outline of said opening, said elastic material and said waistband cooperating when said slip is worn to make said upper body-covering portion substantially form fitting to the upper torso of a wearer; and, shoulder straps connecting the front and rear of said upper body-covering portion.

25 3. A lady's slip, comprising: a skirt portion; a waistband at the upper edge of said skirt portion formed of a material having sufficient circumferential resilience to cause said band to snugly engage the waist of a wearer; an upper body-covering portion secured at its lower edge to said waistband, the front of said upper body-covering portion being formed with an opening in the breast area substantially across the width of said portion and from a point adjacent said waistband upwardly in order that the major portion of a wearer's breasts will not be covered by said upper body-covering portion; elastic material secured to the front of said upper body-covering portion so as to form the outline of said opening, said elastic material and said waistband cooperating when said slip is worn to make said upper body-covering portion substantially form fitting to the upper torso of a wearer; and, shoulder straps connecting the front and rear of said upper body-covering portion.

30 4. A lady's slip, comprising: a skirt portion; a waistband at the upper edge of said skirt portion formed of a material having sufficient circumferential resilience to cause said band to snugly engage the waist of a wearer; an upper body-covering portion secured at its lower edge to said waistband, the front of said upper body-covering portion being formed with an opening in the breast area substantially across the width of said portion and from a point adjacent said waistband upwardly in order that the major portion of a wearer's breasts will not be covered by said upper body-covering portion; elastic material secured to the front of said upper body-covering portion so as to form the outline of said opening, said elastic material and said waistband cooperating when said slip is worn to make said upper body-covering portion substantially form fitting to the upper torso of a wearer; and, shoulder straps connecting the front and rear of said upper body-covering portion.

35 5. A lady's slip, comprising: a skirt portion; a waistband at the upper edge of said skirt portion formed of a material having sufficient circumferential resilience to cause said band to snugly engage the waist of a wearer; an upper body-covering portion secured at its lower edge to said waistband, the front of said upper body-covering portion being formed with an opening in the breast area substantially across the width of said portion and from a point adjacent said waistband upwardly in order that the major portion of a wearer's breasts will not be covered by said upper body-covering portion; elastic material secured to the front of said upper body-covering portion so as to form the outline of said opening; a horizontal elastic crosspiece interconnecting the sides of said opening adjacent the upper edge of said waistband, said waistband being cut away therebelow to define a separate frontal opening, said elastic material and said

40 crosspiece cooperating with said waistband when said slip is being worn to make said upper body-covering portion substantially form fitting to the upper torso of a wearer; shoulder straps inter-

45

5

connecting the upper inner edges of the upper body-covering portion; a buckle carried by each of said shoulder straps whereby the effective length thereof may be adjusted; and, strap means connecting the upper edge of said upper body-covering portion outwardly of said opening with each of said shoulder straps at a point thereon below said buckle.
